(57) **CLAIM**

The ornamental design for a “retail display cart”, as shown and described.

DESCRIPTION

FIG. 1 is a perspective view of a “retail display cart”, showing my new design;

FIG. 2 is a front elevational view thereof;

FIG. 3 is a left side elevational view thereof (and also a mirror image of the right side);

FIG. 4 is a rear elevational view thereof;

FIG. 5 is a top plan view thereof; and,

FIG. 6 is a bottom plan view thereof.

The broken line showing of the environment is for illustrative purposes only and forms no part of the claimed design.
